UNITED STATES PATENT OFFICE

103,871

DESIGN FOR A TOY BOAT

Stanley V. Height, Spring Lake, N. J.

Application October 13, 1936, Serial No. 65,290

Term of patent 3½ years

To all whom it may concern:

Be it known that I, Stanley V. Height, a citizen of the United States, residing at Spring Lake, in the county of Monmouth and State of New Jersey, have invented a new, original, and ornamental Design for a Toy Boat, of which the following is a specification, reference being had to the accompanying drawing, forming part thereof.

The figure is a perspective view of a toy boat showing my new design.

I claim:

The ornamental design for a toy boat as shown.

STANLEY V. HEIGHT.
